UNITED STATES PATENT OFFICE.

EDWIN L. ROBINSON, OF PROVIDENCE, RHODE ISLAND, ASSIGNEE OF ONE-HALF TO
HENRY J. SPOONER, OF PROVIDENCE, RHODE ISLAND.

SWIVEL FOR WATCH CHAINS AND THE LIKE.

1,417,281.

Specification of Letters Patent. Patented May 23, 1922.

Application filed March 23, 1921. Serial No. 454,949.

To all whom it may concern:

Be it known that I, EDWIN L. ROBINSON, a citizen of the United States, residing at Providence, in the county of Providence and 5 State of Rhode Island, have invented a new and useful Swivel for Watch Chains and the like, of which the following is a specification.

The purpose of my invention is to provide 10 a swivel for watch chains and the like in which the tongue controlling spring is entirely concealed within the body of the swivel and the pin on which the tongue is commonly pivoted is dispensed with.

15 To these ends my invention consists in the new and novel construction, combination and arrangement of parts hereinafter described and illustrated in the accompanying drawings, in which,—

20 Figure 1 is an elevation of a swivel embodying my invention.

Figure 2 is a similar view of the same partly in section.

Figure 3 is a view of a V-shaped spring.

25 Figure 4 is a transverse section of the cap which conceals the spring, and on which the swivel tongue is fulcrumed.

Figure 5 is a bottom view of said cap, with the hook and tongue shown in cross 30 section.

Figure 6 is a longitudinal section of the upper portion of the swivel body and of the tongue of the swivel hook, showing a coiled wire spring disposed in said body in engagement with the tongue.

35 Figure 7 is a view of the coiled spring.

Figure 8 is a bottom view of the body of the well known form of swivel body, showing the hook and tongue in cross section and 40 the tongue controlling spring disposed between them.

Figure 9 shows details of the spring engaged end of the tongue.

Like reference letters and numerals indicate like parts where they occur in the several views.

In the drawings: 1 represents the chambered body of the swivel, which may be of any exterior conformation, ornamented or 50 plain.

Within the chamber of said body is a vertically disposed spring arranged and adapted to be connected at one end with the upper end of the swivel latch or tongue to control 55 the lateral movements of the latter. While

said spring may be of any form I have for purposes of illustration shown in Figs. 2 and 3 a two-arm V-shaped spring, as 2, and in Figs. 6, 7 and 9 another form of two-arm spring, as 3. Both of which may be formed 60 of wire.

The chambered portion of the swivel body is open at its lower end (Fig. 6). On its upper end rotatably is mounted in the well known manner the ring 5.

65 The lower open end of said chambered body is tightly closed by an immovable cup-shaped cap 6 (Fig. 4) which is provided in its face near one side with a perforation 8. At the opposite side of said cap face and in 70 alinement with said perforation is rigidly secured one end of the swivel hook or loop 7 (Fig. 5).

75 The upper end 9 of the tongue of the swivel hook is swaged or otherwise thinned, and is near its upper end pierced as at 11, to receive the end of the controlling spring (Figs. 2 and 9). Said tongue is further provided on its inner edge with a laterally directed notch 10 which engages with the 80 edge of the perforation 8 of the cap 6 which thereby serves as a fulcrum for said tongue (Figs. 2, 5 and 9).

85 The hook 7 being secured to the cap 6 and the tongue 4 fulcrumed on said cap the latter is passed over the open end of the chambered body 1 and swaged immovably thereon thereby closing said open end and concealing the spring (Figs. 1 and 2).

90 I have thus provided an efficient and durable swivel for watch chains and the like in which the swivel body is closed at one end, the swivel hook tongue fulcrumed on said closed end for oscillating movement as controlled by a spring concealed within said 95 swivel body. Such spring being preferably of wire, may be of any form.

I claim as my invention, and desire to secure by Letters Patent:

1. A swivel for watch chains and the like 100 comprising a chambered body member open at one end and closed at the opposite end, a ring rotatably mounted on said closed end, a laterally acting spring vertically disposed in said chambered body, a cup-shaped 105 cap immovably secured over and closing said open end of said body member and provided in its face near one side with a perforation, a swivel hook consisting of a loop member and a latch member, one end of said loop 110

member secured to said cap face in alinement with said perforation, and the upper end of said latch member extending through said perforation into said chambered body member and provided with a laterally directed notch in its inner edge engaging said cap at one side of said perforation whereby said latch is held in operative position and fulcrumed on said cap for oscillating movements to open and close the swivel hook, and also provided with means for operatively connecting the upper end of said latch with said spring.

2. In a swivel for watch chains and the like the combination of a hollow body member open at one end, a cap immovably secured over and closing said open end and having in its face near one side a perforation, a swivel hook consisting of a loop member and a latch member, one end of said loop member rigidly secured to the face of said cap in alinement with said perforation, and said latch member protruding through said perforation into said body member and provided in its edge with a laterally directed notch arranged and adapted to engage one side of said perforation whereby said latch member is oscillatingly fulcrumed on said cap, and a spring disposed within said body member in engagement with the upper end of said latch member.

3. In a swivel for watch chains and the like having a hollow body closed at one end and open at the opposite end, a ring rotatably mounted on said closed end, a cap immovably secured upon and closing said

open end and provided near one side of its face with a perforation, a two-arm spring vertically disposed within said hollow body, the combination with said parts of a hook member consisting of a loop member secured at one end to the face of said cap in alinement with said perforation, and a latch member provided in one edge with a laterally directed notch arranged and adapted on the insertion of said latch through said perforation to engage said cap to thereby hold said latch in operative position fulcrumed on said cap for oscillating movements of said latch, and means for operatively connecting said latch member with one arm of said spring.

4. In a swivel for watch chains and the like having a hollow body member, a latch controlling spring disposed therein, and a cap immovably secured on one end of said body member and having in its face near one side a perforation, the combination with said parts of a hook member consisting of a loop portion secured at one end to the face of said cap in alinement with said perforation and a latch member operatively connected to said spring and provided in one edge with a laterally directed notch arranged and adapted to hold said latch in operative position in said perforation fulcrumed on said cap.

EDWIN L. ROBINSON.
